Primary Examiner — Mojtaba Tehrani*(74) Attorney, Agent, or Firm* — Jose Cherson Weissbrot(57) **CLAIM**

The ornamental design for a sight reticle, as shown and described.

DESCRIPTION

The sole view is a front perspective view of a sight reticle, showing my new design.

All the broken lines in the drawings depict portions of the sight reticle, that form no part of the claimed design.

1 Claim, 1 Drawing Sheet(56)
